UNITED STATES PATENT OFFICE.

WILLIAM S. EASTON, OF BABYLON, NEW YORK, ASSIGNOR OF ONE-HALF TO MAX ENGLANDER, OF NEW YORK, N. Y.

FIREPROOF CABINET.

1,032,351.

Specification of Letters Patent.

Patented July 9, 1912.

Application filed January 7, 1911. Serial No. 601,332.

To all whom it may concern:

Be it known that I, WILLIAM S. EASTON, a citizen of the United States, residing at Babylon, in the county of Suffolk and State 5 of New York, have invented certain new and useful Improvements in Fireproof Cabinets, of which the following is a specification.

This invention relates to protecting cabinets for inflammable materials such as oils, 10 varnishes, etc., used in the furniture business, the object of the invention being to provide a cabinet inexpensive to manufacture, but effective to quickly and thoroughly extinguish a fire occurring among the 15 tents of such cabinet.

In the drawings accompanying and forming a part of this specification, Figure 1 is a perspective view of this improved cabinet with a part of one of the doors broken 20 away; Fig. 2 is a sectional view of the upper part of such cabinet; Fig. 3 is a transverse sectional view of the cabinet; Fig. 4 is a view of the fuse member.

Similar characters of reference indicate 25 corresponding parts in the several figures of the drawing.

The cabinet, which may be of any desired shape and construction, is herein shown provided with a bottom, side and rear walls, 30 and a pair of swinging doors. Within the cabinet 2 is located a plurality of shelves 3 of perforated form, and for this purpose they may be made of wire mesh for the reception of the cans or bottles which it may 35 be desired to store therein. At the top of the cabinet there is located a trough 4 for the reception of sand. The bottom 5 of this trough is formed as a perforated bottom, preferably of wire mesh, and below this per- 40 forated bottom is a pair of swinging doors 6 and 7 adapted to swing downward, suitable means being provided for maintaining the doors closed, and thus preventing the falling of the sand into the cabinet. For 45 this purpose the doors are secured in their closed position by suitable bolts 8, one at each side of one of the doors, which is pro- 50 vided with a flange 9 overlapping its com- panion door when in closed position, so that 55 when the bolts are shot the two doors will be maintained in a horizontal position be- 60 neath the perforated bottom of the trough, the bolts projecting into keepers 10 carried by the side walls of the cabinet. To each

bolt there is a chain 11 running to the opposite side of the cabinet and out of an opening 11' in the side wall of the cabinet. To the end of each chain is secured a weight 12 guided by a suitable pulley 12' on the outside of the cabinet. The weight serves 60 to withdraw the bolt. For preventing the action of the weight upon the bolts the two chains are connected by a suitable hook 13 in the form of a fuse adapted to be severed by the heat within the cabinet. On the 65 severing of this fuse the weights will fall withdrawing the bolts and so permit the doors 6 and 7 to fall downward by reason of the weight of the sand thereon and the same to pass through the perforated bottom of 70 the trough to the several shelves and there- through by reason of the perforations there- of to extinguish the fire which may have occurred in the cabinet on any one of the 75 several shelves.

It will be understood, of course, that this improved cabinet, which is entirely closed so that the fire will be confined therein and is preferably portable so that it may be placed in any desired position or changed from 80 room to room as occasion may require, may be used for various kinds of inflammable materials, in garages, and various other places where an article of this kind is 85 needed.

The cabinet may be double walled and will, of course, be lined with some suitable fire proof material as at 14 and 15, such for instance as metal and asbestos, so that any fire which may occur therein will be 90 confined within the cabinet and can be readily and quickly extinguished by the sand carried in the trough, which is automatically re- 95 leased in the manner set forth. By having the shelves formed as perforated shelves the 95 passage of the sand through the shelves will be readily permitted, so that should the fire occur at the bottom of the cabinet it will be as quickly extinguished as though it had 100 occurred on the top shelf.

I claim as my invention:

1. A closed cabinet for the storage of inflammable materials, having one or more perforated shelves therein below the top thereof, a sand-carrying trough at the top 105 thereof provided with a releasable bottom, means located within said cabinet for secur- ing said bottom in its normally closed posi-

- tion, flexible metallic members connected with said means and crossing each other, weighted means connected with said metallic members for releasing said securing means, and a fusible member connecting said metallic members for preventing the action of the weighted means upon said securing means until the severance of said fusible member.
- 10 2. A cabinet for the storage of inflammable materials having one or more perforated shelves therein, a sand carrying trough at the top thereof provided with a downwardly swinging bottom, a plurality of bolts 15 for securing said bottom in its normally closed position, chains connected with said bolts and crossing each other and passing to the outside of the cabinet, weights carried by said chains, and a fusible member 20 connecting said chains and effective to prevent the action of the weights upon the bolts until the severance of said fusible member

on the occurrence of a fire within the cabinet.

3. A cabinet for the reception of inflammable materials having one or more perforated shelves therein, a sand carrying trough at the top thereof and provided with a pair of downwardly swinging doors, bolts for securing said doors in their normally closed position, flexible metallic members connected with said bolts and crossing each other and provided with weights for withdrawing the bolts, and a fusible member connecting the chains for preventing the action 35 of the weights thereon except on the occurrence of a fire within the cabinet.

Signed at 1822 Park Row Bldg., New York, N. Y., on the 31st day of December, 1910.

WILLIAM S. EASTON.
